[57] CLAIM

The ornamental design for a miniature hurricane lamp
for dollhouses and the like, substantially as shown and
described.

DESCRIPTION

FIG. 1 is an elevational view of a miniature hurricane
lamp for dollhouses and the like showing my new de-
sign, the opposite side being identical to the side shown;
FIG. 2 is a top view of FIG. 1; and
FIG. 3 is a bottom view of FIG. 1.
